UNITED STATES PATENT OFFICE.

NICHOLAS J. WINLUND, OF ROCKFORD, ILLINOIS, ASSIGNOR TO WINLUND KNITTING COMPANY, OF ROCKFORD, ILLINOIS, A CORPORATION OF ILLINOIS.

KNITTING-MACHINE

No. 927,915.

Specification of Letters Patent. Patented July 13, 1909.

Application filed September 9, 1907. Serial No. 391,856.

To all whom it may concern:

Be it known that I, NICHOLAS J. WINLUND, a citizen of the United States, residing at Rockford, in the county of Winnebago and 5 State of Illinois, have invented certain new and useful Improvements in Knitting-Machines, of which the following is a specification.

This invention relates to automatic knitting machines and refers particularly to circular knitting machines adapted to form two or more kinds of web, as, for example, plain-stitch web and rib-stitch web.

One of the objects of this invention is the 15 production of a machine adapted to knit a plurality of forms of web with one set of needles.

The invention also relates to the other improvements in knitting machines herein- 20 after set forth.

In the accompanying drawings, Figure 1 is an elevation of a portion of a circular knitting machine embodying the features of my invention. Fig. 2 is a vertical central section therethrough. Fig. 3 is a horizontal sectional view taken on the plane of dotted line 3-3 of Fig. 2. Fig. 4 is a horizontal section on dotted line 4-4 of Fig. 2. Fig. 5 is a view of a portion of the devices for transferring 25 ring needles from the needle cylinder to the needle dial. Fig. 6 represents one of the needle jacks. Fig. 7 is a detail view of the needle operated by said jack. Fig. 8 illustrates another form of needle and the jack 30 for operating it. Fig. 9 shows a jack for operating the form of needle represented in Fig. 7. Fig. 10 is a detail view of one of the sinkers.

In the production of rib-stitch web by the 40 machines now in use, a set of cylinder needles and a set of dial needles are employed. My invention contemplates the production of rib-stitch web by means of the set of needles used for the knitting of plain-stitch 45 web, said needles being divided into two groups when rib-stitch fabric is to be produced, or, in other words, certain of the needles being shifted from the needle cylinder to the needle dial. This result I accomplish by 50 the use of the double-ended needle shown in Figs. 2 and 7. Said needle comprises what may be termed a cylinder needle and a dial needle, the shanks of which needles are pref-

erably formed integral and extend at an angle with each other.

I have herein shown only so much of a 55 complete circular knitting machine as is necessary to impart an understanding of the present invention.

In the supporting framework 1 is rigidly 60 mounted a bed 2 and a needle cylinder 3, said cylinder having radial slots 4 therein, within which the cylinder jacks and the knitting needles operate. A shaft 5 is rigidly supported in the framework above, and axially aligned with, the needle cylinder 3, and to the lower end of said shaft is fixed a dial 6 65 provided with radial slots 7. Fixed to the rod 5 above the dial 6 is a head 8 consisting, in this instance, of two cylindrical members 9 and 10 provided with aligned vertically 70 extending grooves 11. Within the grooves 11 are pivotally mounted dial jacks 12 (Figs. 2 and 10) having openings 13 in their lower ends for the reception of the knitting needles 75 to be hereinafter described.

The needle cylinder 3 is provided at its upper end with an outwardly-extending annular flange forming an inwardly-inclined web-holder bed 14 having slots 15 therein in which the web-holders 16 are mounted. Rotatably mounted upon the bed 14 is the web-holder cam ring 17. Said cam ring has an annular downwardly-extending flange 18 to which is secured a bevel gear ring 19. Rotatably mounted upon the needle cylinder 3 is the knitting cam ring 20 bearing upon its inner periphery knitting cams of any common or preferred form for operating the cylinder jacks. 20^a (Fig. 2) is an annular ledge upon 80 which the knitting butts of the needle jacks rest, the knitting cams being located in operative alignment with said ledge. The space above the ledge 20^a, except at the point at 85 which the knitting cams are situated, is open, as shown in Fig. 2, to permit the needle jacks to rise, as will appear hereinafter. The knitting cam ring 20 is rigidly secured to the bevel gear 19 by means of hangers 21.

Any suitable means may be provided for 100 operating the dial jacks 12. In the present embodiment there are fixed to the web-holder cam ring 17 two vertically-extending posts 22 joined at their upper ends by means of a cross arm 23, a bearing 24 being provided in 105 said cross arm for the shaft 5. The lower

ends of the jacks 12 are forced inwardly at the proper times during the operation of knitting by means of a cam 25 fixed to one of the posts 22 and arranged to move through 5 the space between the members 9 and 10 composing the head 8. The jacks 12 are tilted in the opposite direction by a cam ring 26 fixed to the posts 22 in position to act upon the upper ends of said jacks. The cylinder-needle knitting-cam ring 20, the web-holder cam ring 17, and the dial-needle cams 25 and 26 are rotated by a bevel spur gear 27 fixed upon a shaft 28 and meshing with the bevel gear 19. Power to drive the various 10 mechanisms of the machine may be applied to said shaft by means of the drive pulley 29.

The double-ended needle 30 (Fig. 7) employed in the embodiment herein shown of my invention virtually consists of a cylinder 20 needle 31 and a dial needle 32, the shanks of which needles extend at an angle with each other. In the shank of the cylinder needle 30 is formed an offset 33 for the purpose of giving the needle shank sufficient thickness 25 to prevent transverse movement of said needle in the opening 13 of the jack 12.

As hereinbefore stated, when rib-stitch web is to be formed, certain of the needles are transferred from the needle cylinder to 30 the needle dial. It is obvious that only the needles which are thus transferred need be of the double-ended form shown in Fig. 7, and that those which do not leave the needle cylinder may be of any common or preferred form, as, for example, the needle 34 shown in Fig. 8. The needle 34 has a butt 35 for engagement by its operating jack. The relative arrangement of the needles 30 and 34 in the needle cylinder 3 depends, of 35 course, upon the kind of rib-stitch web to be produced. In the knitting of one-and-one web, for example, the needles 30 and 34 alternate regularly in position in the grooves 4 of said cylinder. For the needles 30 I provide jacks 36 having notches 37 in their upper ends of proper size to receive the dial needle portion 32, and for the needles 34 jacks 38 are provided having notches 39 therein to receive the butts 35 upon said needles.

50 The means for elevating the needles 30 into the jacks 12 in the head 8 will next be described. The means herein shown for this purpose is arranged to elevate one-half of said needles at a time by devices acting at 55 opposite sides of the needle cylinder. Each of said devices comprises a vertical post 40 rigidly supported in the machine frame by means of a bracket 41. Upon said post are slidably mounted two members 42 and 43 each in the form of a half-ring. The member 42 is provided with a sleeve 44 which is slidably mounted upon the post 40, and the member 43 has a sleeve 45 fitting loosely upon the sleeve 44. A pin 46 (Fig. 1) fixed 60 to the member 43 passes freely through an

opening 47 in the lower member 42 and supports the member 43 in a plane above the bed 2. Coiled springs 48 bearing at their ends upon the upper ends of the sleeves 44 and 45 and the bracket 41 tend to move the members 42 and 43 into their lowermost positions as shown in Fig. 1 and at the left-hand side of Fig. 2. The jacks 36 are provided at their lower ends with butts 49 adapted to lie between the members 42 and 43.

70 The means for elevating the members 42 and 43 to divide the needles into two groups for rib-stitch knitting comprises a rock shaft 50 rotatably mounted in bearings 51 at each side of the needle cylinder 3. Upon one end of said shaft is fixed an arm 52 adapted to underlie the member 42. Upon the other end of said shaft is non-rotatably mounted an arm 53 which is arranged to have a pivotal movement with reference to said shaft for a 80 purpose to appear hereinafter. When in the position shown in Fig. 1, the arm 53 lies in the path of a plunger 54 slidably mounted in a guide member 55 fixed in the machine frame. Said plunger carries a pin 56 adapted to be engaged by a cam 57 fixed upon the shaft 28 for projecting said plunger against the arm 53 and thereby rocking the shaft 50 to raise the members 42 and 43. The pin 56 travels in a slot 58 formed in one side of the 85 guide member 55. A spring 59 connected at one end to a stationary part of the framework and at its other end to a pin 60 fixed to the plunger 54 restores said plunger to its inward position after the cam 57 has acted 90 upon said plunger. A slot 61 is provided in the guide member 55 for each of the pins 60. The arm 53 is arranged to be pivotally moved into and out of the path of movement of the plunger 54 by a pattern mechanism 105 (not shown) in order that the needles 30 may be transferred to the needle-dial 6 only at the proper times. At a suitable point upon the rock shaft 50 is fixed an arm 62 carrying a pin 63. Pivotally mounted in the supporting frame is a detent 64 having a notch 65 in its upper end adapted to receive the pin 63 and thereby hold the members 42 and 43 in the elevated position. A spring 66 fixed to the detent 64 and to a stationary part of the 115 framework tends to move said detent into engagement with the arm 62. For moving the detent 64 out of engagement with said arm I have provided, in this instance, a bell-crank lever 67 pivoted in the supporting 120 frame, one arm of which lever carries a pin 68 lying at one side of the detent 64. The other arm of said bell-crank lever is connected with a pattern mechanism (not shown) of any common or preferred construction, for withdrawing the detent at the proper time to permit the springs 48 to restore the needles 30 to the plain-stitch knitting position.

125 The needles 30 are not disengaged from 130

their jacks 36 when raised into the rib-stitch knitting position. In order, however, to provide space for the yarn acted upon by the dial needle portion 32 of said needles when in use I have provided means for drawing the upper ends of the jacks 36 outward a slight distance. In Fig. 4, 69 indicates a member fixed to the web-holder cam ring 17, said member having a cam groove 70 in its lower side into which the studs 71 upon the upper ends of the jacks 36 enter. The form of said cam groove is such that the jacks 36 engaged by the member 69 in its rotation are moved outwardly slightly at the required time, said 15 jacks rocking upon their butts 49.

The bobbin or bobbins x are supported in any suitable way, as, for example, upon a cross bar 72 fixed with relation to the cross-bar 23 and therefore rotating with the knitting cams. The yarn passes through eyes 73 upon one of the posts 22 and through a yarn carrier 74 fixed to the web-holder cam ring 17.

A motion-changing mechanism of any 25 common or preferred form may be employed for changing the movements of the knitting and web-holder cams from rotary to oscillatory, and vice versa.

I have omitted illustration of the means 20 for throwing the needles into and out of action in the formation of the heel and the toe, as any desired mechanism may be employed for that purpose. Such a mechanism is illustrated in Patent No. 478,673, issued to 35 me on July 12, 1892. In applying said mechanism to the present machine, the radially disposed subjacks illustrated in the patent would be located below the plane of the members 42, the inner ends of said sub- 40 jacks engaging downwardly-projecting extensions upon the needle jacks.

In operation, when plain-stitch web is being formed all of the needles are in the plain-stitch knitting position, as shown at the 45 left-hand side of Fig. 2, and the pattern mechanism holds the arms 53 out of the path of movement of the plungers 54. During the formation of plain-stitch web the members 42 and 43 are separated sufficiently to 50 permit of the reciprocatory movements of the jacks 36 imparted to them by the cams upon the inner face of the knitting cam ring 20. When ribbed fabric is to be produced the pattern mechanism automatically throws 55 the arms 53 into the path of the plungers 54, which plungers, striking first one arm and then the other, successively rock the shafts 50 and lift the members 42 and 43, as shown at the right-hand side of Fig. 2. The knitting needles carried by the jacks engaged by 60 said members (to wit, the jacks 36) are thereby elevated into the openings 13 in the lower ends of the jacks 12 of the head 8, the loop of 65 yarn carried by each of said needles slipping over the shank of the cylinder-needle section

31 onto the shank of the dial-needle section 32. The transfer of needles takes place first at one side of the cylinder and then the other. The needles at each side are transferred when the knitting cams are at the 70 other side. The jacks 12 are held by the cam 26 in proper position to receive the needles when the latter are elevated by the members 42 and 43. The jacks 36 are held in elevated position by means of the detents 75 64 which are automatically moved into engagement with the pins 63 upon the arms 62 by springs 66 as soon as said arms are raised by the plungers 54. The needles 30 are now reciprocated within the slots 7 of the dial 6 80 by the cam 25 and the cam ring 26, and the needles 34 reciprocated within the slots 4 of the cylinder 3 by the knitting cam ring 20, for the production of rib-stitch web. When plain-stitch fabric is again to be produced, 85 the pattern mechanism rocks the bell-crank levers 67 to withdraw the detents 64, whereupon the springs 48 lower the jacks 36 into the plain-stitch knitting position, withdrawing the needles 30 from the jacks 12, the 90 loops of yarn carried by said needles sliding over the shanks thereof. The web-holder bed 14 being inwardly inclined the web-holders 16 are given a downwardly directed movement as they travel inwardly, said web-holders thereby serving to feed the work downwardly and making the use of a weight 95 unnecessary for that purpose.

It will be apparent to those skilled in the art that various mechanical embodiments of the invention are possible, and I therefore do not limit myself to the arrangement and construction shown.

I claim as my invention:

1. A knitting machine for automatically producing a plurality of forms of the web comprising two needle beds extending at an angle with relation to each other, a needle, and automatic means for moving said needle from one bed to the other. 105

2. A knitting machine for automatically producing a plurality of forms of the web comprising a needle cylinder, a needle dial, a needle, and automatic means for moving said needle from said needle cylinder to said needle dial. 110

3. A knitting machine comprising two needle beds, one of said beds being circular, needles in said circular needle bed, and means for simultaneously transferring to the other bed needles disposed around a portion of the circumference of said circular bed. 115

4. A knitting machine comprising two needle beds, needles in one of said beds, devices at each side of said beds for transferring needles from one bed to the other, and means for alternately actuating said transferring devices. 120

5. A knitting machine comprising a cylindrical needle bed and another needle bed, 125

- needles, and two mechanisms acting at opposite sides of said cylindrical bed for moving needles from said cylindrical bed to said other needle bed and for returning the needles to said cylindrical bed. 5 other, means for holding the upper member separated from the lower, spring means tending to move said members downward, and means for raising the lower member, the latter carrying with it the upper member. 50
6. A knitting machine comprising a cylindrical needle bed and another needle bed, needles, and two mechanisms acting at opposite sides of said cylindrical bed for moving needles from said other bed to said cylindrical bed and for returning the needles to said cylindrical bed. 6. A knitting machine comprising a cylindrical needle bed and another needle bed, needles, semicircular devices surrounding said cylindrical bed and operatively engaging said needles, and means for moving said devices to transfer said needles from one of said needle beds to the other. 55
7. A knitting machine comprising a needle cylinder, a needle dial, double-ended needles, and two mechanisms acting at opposite sides of said cylinder for moving said needles from said cylinder to said dial and vice versa. 15 14. A knitting machine comprising two needle beds, needles adapted for use in either bed, two devices for transferring said needles from one bed to the other, each of said devices comprising a pivoted arm, and means for alternately swinging said arms in opposite directions. 65
8. A needle-moving mechanism for knitting machines comprising a post, two members slidably mounted on said post, and means for sliding said members in opposite directions. 20 15. A knitting machine comprising two needle beds, needles adapted for use in either bed, two devices for transferring said needles from one bed to the other, each of said devices comprising a pivoted arm, and a cam located between said arms and arranged to swing them alternately in opposite directions. 70
9. A needle-moving mechanism for knitting machines comprising a post, two members slidably mounted on said post, means for holding said members separated to permit of the knitting action, and means for sliding one of said members against the other and sliding both to move a needle. 25 16. A needle-moving mechanism for knitting machines comprising a needle-engaging member, means for moving said member comprising a pivoted arm, means for swinging said arm in one direction, means for holding said arm in the position to which it is swung, and means for withdrawing said holding means. 80
10. A needle-moving mechanism for knitting machines comprising two opposed members arranged to receive between them the device to be moved, means for holding said members separated to permit of the knitting action, and means for moving one of said members to move said device. 30 17. A knitting machine having a needle cylinder, a needle dial, double-ended needles transferable from the cylinder to the dial and vice versa, cylinder jacks having notches therein to receive one end of each of said double-ended needles, and means for elevating said jacks to transfer their needles and for moving said jacks outwardly to provide room in said notches for the yarn. 85
11. A needle-moving mechanism for knitting machines comprising two opposed members arranged to receive between them the device to be moved, said members being movable with relation to each other, means for holding said members separated to permit of the knitting action, and means for moving said members to hold and move said device. 40 90
12. A needle-moving mechanism for knitting machines comprising a support, two members vertically movable on said support, one of said members being above the
